(57) **CLAIM**

The ornamental design for a lid for food container, as shown and described.

DESCRIPTION

FIG. 1 is a perspective view of a lid for food container showing our new design;

FIG. 2 is a top view thereof;

FIG. 3 is a bottom view thereof;

FIG. 4 is a front view thereof;

FIG. 5 is a rear view thereof;

FIG. 6 is a left side view thereof;

FIG. 7 is a right side view thereof;

FIG. 8 is a top view of the lid for food container of FIG. 2 shown with the handles moved to a second position to expose the air holes; and,

FIG. 9 is an exemplary perspective view of the lid for food container of FIG. 1 shown in a use configuration with environment of a food container.

The broken lines in FIG. 9 depict the environment of a food container that forms no part of the claimed design.
